FINGER STALL OR SIMILAR ARTICLE

Charles E. Jones, Chicago, Ill., assignor to
Translon Company, Newark, N. J., a corpora-
tion of New Jersey

Application August 19, 1952, Serial No. 21,107

Term of patent 7 years

(Cl. D74—1)

To all whom it may concern:

Be it known that I, Charles E. Jones, a citizen of the United States, residing at Chicago, in the county of Cook and State of Illinois, have invented a new, original, and ornamental Design for a Finger Stall or Similar Article, of which the following is a specification, reference being had to the accompanying drawing, forming a part thereof.

Fig. 1 is a top plan view of the finger stall or similar article showing my new design;

Fig. 2 is a bottom plan view of the finger stall or similar article;

Fig. 3 an end elevational view thereof; and

Fig. 4 is a side elevational view of the finger stall or similar article.

I claim:

The ornamental design for a finger stall or similar article, substantially as shown.

CHARLES E. JONES.
